[57] CLAIM

The ornamental design for a door handleset, as shown and described.

DESCRIPTION

FIG. 1 is a front elevational view of my new design of a door handleset;

FIG. 2 is a right side view of my new design of the door handleset, a left side view of my new design of the door handleset being a mirror image of the right side view thereof;

FIG. 3 is a rear view of my new design of the door handleset;

FIG. 4 is a top view of my new design of the door handleset;

FIG. 5 is a bottom view of my new design of the door handleset; and,

FIG. 6 is a perspective view of my new design of the door handleset.

FIG. 1

FIG. 2

*FIG. 3**FIG. 4**FIG. 5*

FIG. 6
